UNITED STATES PATENT OFFICE.

FRANCESCO SKERL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,243,992.

Specification of Letters Patent. Patented Oct. 23, 1917.

Application filed February 17, 1912. Serial No. 678,192.

To all whom it may concern:

Be it known that I, FRANCESCO SKERL, a citizen of Austria, residing at Dayton, in the county of Montgomery and State of Ohio, 5 have invented certain new and useful Improvements in Cash-Registers, of which I declare the following to be a full, clear, and exact description.

This invention relates to accounting machines and more particularly to the accumulating mechanism thereof.

Heretofore calculating machines have been designed to add amounts by operating the totalizer in an additive direction, and to 10 subtract amounts by operating the totalizer in a subtractive direction. The present applicant is thought to be the first who has designed an accumulating device adapted to 15 accumulate amounts by operating the accumulator and actuators the shortest possible 20 extent, whether it be in an additive or subtractive direction, and to provide mechanism for automatically effecting the movement of the actuators and accumulator and controlling said movement both as to direction and 25 extent.

The principal object of this invention is to provide an accumulator, the elements of which are moved in the shorter distance in 30 the accumulating of items, by the employment of subtraction of complements of amounts.

Another object of this invention is to provide actuators for the elements of the accumulator, which actuators are variably movable in different directions for the purpose of effecting the accumulation of items on the accumulator.

A further object of this invention is to 40 provide manipulative devices for determining both the direction and extent of movement of the actuators.

A still further object of this invention is to provide normally inoperative transfer devices which are rendered operative by the 45 accumulating elements in either direction of movement of said elements.

With these and incidental objects in view, the invention consists in certain novel features of construction and combinations of parts, the essential elements of which are

set forth in appended claims, and a preferred form of embodiment of which is hereinafter described with reference to the drawings which accompany and form part 55 of the specification.

Figure 1 represents an end elevation showing the operating gearing for the machine embodying the above mentioned improvements.

Fig. 2 is a central transverse sectional view through the improved machine.

Fig. 3 is an enlarged sectional view showing the accumulator and the actuators therefor, the various parts being in normal 65 position.

Fig. 4 is an enlarged sectional view through the accumulator, showing said accumulator in engagement with the intermediate gears which form a part of the actuators.

Fig. 5 is a detail elevation of the operating mechanism for moving the accumulator into engagement with the actuators.

Fig. 6 is a detail view of one of the key 75 operated slides and connections for controlling the engagement of its corresponding actuator with the driving mechanism.

Fig. 7 is a detail view of the key latching 80 detent.

Fig. 8 is a detail view of the cam and connections for operating the key detent shown in Fig. 7.

Fig. 9 is a detail view of the cam and pitman for alining the indicating mechanism.

Fig. 10 is a detail view of the operating mechanism for controlling the engagement between the actuators and the driving mechanism.

Heretofore in accounting machines the elements of the accumulator were always driven in one constant direction in the accumulating of items. With the improved mechanism about to be described the accumulator elements are always driven to add in the shorter direction, that is to say, if the elements stand at zero and it is desired to enter an item thereon including a series of nines, the elements instead of being moved 100 nine spaces in an additive direction, as heretofore, are moved in a subtractive direction

one space only. In entering any of the digits from one to five, the accumulator elements are moved in an additive direction, but when the digits from six to nine are entered, the said elements are moved in a subtractive direction distances corresponding to the complement of the digit being accumulated. It is immaterial in which direction the elements are moved in entering the digit five, as in either case the element is moved five spaces and it could be arranged to move in a subtractive just as well as in an additive direction, but as shown in the drawings, the digit five is entered by moving the accumulator elements in an additive direction.

The construction outlined operates on a principle which as far as known is novel in the art, namely, the principle of complementary subtraction. For example, if 762 appears on the totalizer and the number 375 is to be added, this may be done either by direct addition or by subtracting the complement of each digit of the number 375, that is by subtracting 735. In either case the numeral wheels would indicate 037, and, neglecting questions of the transfer mechanism, this is the true result. The machine might, therefore, be designed to subtract in every case the complement of the amount to be added. The machine to be described, however, does not do this. It adds directly amounts from one to five units but subtracts the complements of amounts from six to nine units. Therefore the totalizer wheels are never moved more than five units at a time and may be moved either forwardly or reversely to add or subtract respectively, depending upon the amount to be added.

It will be clear that the transfer devices usually employed in totalizing machines will not be sufficient to take care of an operation of the type outlined. The wheels may move additively and therefore the ordinary type of transfer is necessary, that is a transfer is required when any wheel passes from nine to zero positions in an adding direction. However, a transfer may be required if a wheel moves in the subtracting direction. For example, if the totalizing wheels indicate 14 and 9 is added by the subtraction of 1, clearly the result should be 23 and this requires a transfer movement to be given to the tens wheel. However, a transfer is not necessary at every subtracting movement. For example, the wheels may stand at 11 and 8 be added thereto by subtracting 2. This reverse or subtracting movement of two steps of the unit wheel will clearly bring it to indicate 9, but no transfer to the tens wheel should take place.

It will be seen that in every case the question whether or not a transfer should occur on a subtracting movement of any wheel is determined by the question whether the

wheel passes the zero position in a subtracting direction. If the wheel merely reaches the zero position, then a transfer should take place, but if the wheel passes beyond the zero position, then a transfer is not required. Therefore the transfer mechanism which operates when the wheels move subtractively may be constructed to be tripped or set for operation at any subtracting or reverse movement of any totalizer wheel, but should be reset if the wheel passes or leaves the zero position thereof. In the present case a single transfer device for the wheel is provided, effective in either adding or subtracting directions of movement. In the adding direction it operates in a manner well known in the art. In the subtracting direction it is tripped by the first movement of any totalizer wheel and remains tripped and is effective unless the totalizer wheel passes through its zero position, when it is reset or rendered ineffective.

The actuators for the accumulator elements are arranged to be moved variable distances in different directions in order to impart an additive or subtractive movement to the accumulator elements, the extent and direction of movement of the actuators being controlled by manipulative devices in the form of keys. Suitable mechanism is provided for positioning a series of indicators in accordance with the adjustment of the actuators.

The machine to which these improvements have been applied comprises a plurality of banks of value keys 1 which are guided in key frames 2, the latter being supported by transverse shafts 3 and 4, which in turn are supported by the side frames 5 of the machine. The keys 1 are normally held in their outermost positions by coil springs 6, which surround the inner reduced portion of said keys, the ends of said springs abutting against shoulders formed by the reduced portion of said keys and a flange formed upon a portion of the key guide frame 2. Adjacent to each bank of keys is a detent plate 7 (Figs. 2 and 7) which has projecting therefrom lugs 8, which, when any of the keys is depressed, engage with shoulders 9 formed on the keys and latch them in their depressed positions. Each detent plate is pivotally supported by parallel links 11, which are pivotally mounted upon the key frame 2 by studs 12 screwed into said key frame. Each of the detents is held with its lugs 8 in contact with the upper surfaces of the keys 1 by springs 13.

If a key has been depressed by mistake it may be released by the operation of a lever 130 which is secured to one end of the lowermost shaft 3 (Figs. 2 and 7). Secured to and projecting rearwardly from the shaft 3 is a plurality of arms 131, one for each bank

of keys. Each of these arms is directly beneath the lowermost supporting links 11 of the detents 7 and by this means the detents will be elevated to release the key or keys depressed upon the rocking of the shaft 3 by the lever 130. The keys are also released by another means near the end of the operation of the machine as hereinafter described.

Coöoperating with each bank of keys is an actuator 14 (Figs. 2 and 3) which is pivotally mounted upon a stud 15 projecting from its corresponding key frame 2. Pivoted adjacent to the actuator 14 of each bank is the driving mechanism therefor, which comprises two segmental plates 16, which are simultaneously moved in opposite directions as hereinafter more fully described. Each of the actuators 14 carries two latching devices, which are constructed to connect the actuator with the plates 16 of the driving mechanism. Each of these latching devices comprises a sliding arm 17 supported by parallel links 18 which are pivotally mounted upon the actuator 14. Projecting from the arms 17 of each of the latching devices is a stud 19, which plays in a forked portion 20 of a multi-pronged lever 21, the latter being pivotally mounted as at 22 upon the actuator 14. Projecting from one of the prongs of each of the levers 21, carried by each of the actuators 14, is a boss 23 and projecting from said boss is a stud 24. Engaging with the boss 23 and stud 24 of the uppermost lever 21 of each of the actuators 14 are arms 25 and 26 respectively, the former being secured to the shaft 4 while the latter is loosely mounted upon said shaft and is of a bell crank formation as plainly shown in Fig. 2. The upper end of the vertical portion of the bell crank 26 is provided with an angled slot 27 in one portion of which rests a pin 28 projecting from a bell crank 29, which is supported by the stud 12 projecting from the key frame. The other end of the bell crank 29 is pivoted to the upper end of a plate 30, the lower end of which is pivoted to a link 31, which is supported by the lower stud 12. This plate 30 has a series of inclined notches 32 formed therein, which coöperate with the key pins 33 of the five uppermost keys, and said plate is also provided with a series of four radial slots 34 with which coöperate the pins 33 of the four lowermost keys. From this it will be seen that it will be impossible to press a key of the lowermost series and one of the uppermost series in the same bank owing to the different angles of the slots 32 and 34 cut in the plates 30, the purpose of which is to prevent the engagement of both of the latching devices carried by the actuator 14 with their respective driving segments 16 as will more fully hereinafter appear.

A spring 135, connected at its ends to

pins 136, one of which projects from the plate 30 and the other projects from the key frame 2 through a slot in the plate, holds the plate 30 in the position shown in Fig. 2 with the pin 28 of the supporting bell crank link in one end of the angle slot 27 of the lever 26.

From the above description and by reference to Fig. 2 it will be seen that when any one of the five uppermost keys is depressed the plate 30 will be moved downwardly by the pin 33 of the depressed key contacting with the inclined wall of its companion slot 32. This lowering of the plate will rock the arm 29 in an anti-clockwise direction so as to carry the pin 28 projecting from the rearward portion thereof in the horizontal portion of the slot 27, thereby permitting the rocking of the bell crank arm 26 in an anti-clockwise direction. This rocking of the arm 26 would immediately take place upon the depressing of the key by a spring 35 rocking the lever 21, if it were not for the arm 25 which engages the boss 23 on the lever 21. Spring 35 is interposed between a stud 36 projecting from the actuator 14 and one of the arms of the lever 21. Upon the very beginning of the operation of the machine, after a key has been depressed, the arm 25 will be carried away from the boss 23 and thereby permit the spring 35 to rock the lever 21 in an anti-clockwise direction. This rocking of the lever will move the bar 17 of the upper latch device inwardly so as to be engaged by a shoulder 37 formed upon one of the driving segments 16. Upon the further operation of the machine the segment 16 coöperating with this latch device will be moved in an anti-clockwise direction and, through bar 17 of the uppermost latch device, drive the actuator in a similar direction, the extent of movement imparted to the actuator 14 by the driving segment 16 being determined by the depressed key. As the actuator 14 is moved along by its driving segment 16 a prong 38 of the lever 21 will contact with the inner end of the depressed key just as the actuator is moved an extent corresponding to the key depressed, and as the driving segment 16 continues its movement in a counter-clockwise direction will cause the withdrawal of the arm 17 from engagement with the shoulder 37 of the driving segment by the rocking of the lever 21 in a clockwise direction. This withdrawal of the arm 17 from engagement with the shoulder 37 will cause the outer bevel end of said arm to enter one of a series of notches 39 formed in a latch plate 40 secured to the corresponding key frame, and thereby latch the actuator 14 from accidental displacement, the inner end of the arm 17 riding upon the surface of the segment 16 while said segment con-

tinues its movement in an anti-clockwise direction.

This segment is given a movement of about 45 degrees in an anti-clockwise direction and then returned in a clockwise direction to its normal position. As the driving segment is returned to its normal position the rearward edge thereof will contact with the flange 41 projecting from the actuator 14 and return said actuator to normal position, the arm 17 being permitted to disengage from the latch plate 40 by the reduced portion of the driving segment forming the shoulder 37 presenting itself to the inner end of the arm 17, which then will be rocked into said reduced portion by the spring 35 interposed between the lug 36 and one of the arms of the lever 21. As the parts reach normal position the boss 23 of the lever 21 will be engaged by the arm 25 and thereby rock said lever 21 in a clockwise direction so as to disengage the arm 17 from the shoulder 37 of the driving segment 16.

Coöoperating with the four lowermost keys of each bank is a plate very similar to the plate 30, which coöperates with the five uppermost keys but with the slots 32 and 34 formed therein reversely arranged, that is, the cam slots 32 are at the lower portion of the plate coöperating with the four lowermost keys while the radial slots are formed in the upper portion of the plate and coöperate with the five uppermost keys. This plate is supported upon the aforesaid studs 12 by arms similar to the arms 29 and 31 as described in connection with the first mentioned plate 30. A latching mechanism carried by the actuator 14 for connecting said actuator with one of the driving segments 16 is controlled by the four lowermost keys in identically the same manner as the heretofore described latching device controlled by the five uppermost keys, and it is thought that a detailed description of said latching device and the control thereover by the keys coöperating therewith need not be given, it being sufficient to state that when this latching device connects the actuator 14 with the driving segment 16, which is driven first in a clockwise direction and then returned in an anti-clockwise direction to its normal position, the said actuator will be correspondingly moved, from which it will be noted that the actuator is driven in an opposite direction when under the control of the four lowermost keys than when it is under the control of the five uppermost keys of the bank. The same reference numerals are used to identify like parts of the two latching devices and by thus identifying the several parts it is thought their operation will be clearly understood. A number of the reference numerals have been left off of Fig. 2 for fear that the lead lines to said numerals would interfere with the reading of said

figure, but all of said numerals are shown in Fig. 3 which is an enlarged view of Fig. 2.

The arms 25 which contact with the bosses 23 of the upper and lower latching devices carried by the actuators 14 are secured to the shafts 4 and are arranged to be withdrawn simultaneously from engagement with their respective bosses 23 by a link 42, which connects arms 43 secured to and projecting in an opposite direction from the shafts 4 (Fig. 10). The uppermost one of these shafts 4 has extending forwardly therefrom an arm 44 which is connected to the forward end of a pitman 45, the lower and rearward end of which is forked so as to straddle a rotary shaft 46. This pitman near its rearward end has projecting therefrom a roller 47 which plays in a cam groove 48 formed in a disk 49 secured to the shaft 46. From the shape of the cam groove 48 in the disk 49, as shown in Fig. 10, it will be seen that upon the beginning of the rotation of the shaft in the direction of the arrow in said figure, the pitman will be moved downwardly and rearwardly which will rock the uppermost shaft 4 in an anti-clockwise direction, while the lower shaft 4 will be rocked in a clockwise direction by the link connection 42 heretofore described. The withdrawal of the arms 25 from the bosses 23 of the levers 21 of the latching or connecting mechanism occurs immediately upon the operation of the machine and before the driving segments 16 have started to move. The purpose of this early operation of the arms 25 is to insure the engagement of the actuator with the driving segments previous to the movement of said segments.

The segments 16 are connected by links 470 to arms 480 secured to rock shafts 490, the latter being suitably supported in the side frames 5 of the machine. Secured to the lowermost shaft 490 is a bell crank lever 50, the ends of which are provided with rollers 51 and 52. The roller 51 rides upon the surface of a cam disk 53 while the roller 52 bears against the surface of a cam disk 54, the disks being spaced apart by a plate 55, and suitably secured to the rotary shaft 46. The arm of the bell crank 50 carrying the roller 51 is connected by a link 56 to an arm 57 secured to the upper rock shaft 490. The purpose of this connection between the bell crank 50 and arm 57 is to insure the simultaneous rocking of the shafts 490. The cam disks 53 and 54 are so shaped as to rock the bell crank 50 first in a clockwise direction and then back to normal position. This rocking of the bell crank 50 will, through the link 56 and arm 57, rock the upper shaft 490 first in an anti-clockwise direction and then back to its normal position. This rocking of the shaft 490 will, through the links 470 and arms 480, rock the upper driving segment 16 in an anti-clockwise direction

and the lower driving segment in a clockwise direction, each to an extent of about 45 degrees, after which said driving segments are returned to their normal positions with the rock shafts 490.

5 The accumulator about to be described is so constructed that the elements thereof are capable of being driven in different directions in accumulating the total thereon.

10 When an amount from one to five is to be accumulated by any one of the accumulator elements the latter is moved in an additive direction an extent corresponding to the digit to be accumulated. If it is desired to enter an amount represented by a digit 15 above five upon one of the accumulator elements, the element is moved in a subtractive direction an extent corresponding to the complement of the digit to be accumulated; that is, if six is to be entered upon the accumulator, the element is moved in a subtractive direction four spaces, which is the complement of six, or if nine is to be accumulated, the element is moved subtractively one step.

20 Mounted upon a transverse shaft 58, which is located below the key banks and in front of the actuators 14, is a series of gears 59, one for each actuator, and which are constantly in mesh with said actuators and consequently receive the same degrees of movement as are imparted to the actuators. In front of the gears 59 are located the elements 60 of the accumulator. Each of these 25 elements has secured thereto a pinion 61, which is arranged to be engaged with the pinions 59 and to be driven thereby. These accumulator elements 60 are loosely supported upon a shaft 62 which in turn is supported by side arms 63 of the accumulator frame. These arms are connected by a cross bar 64 and are loosely mounted at their lower ends upon a shaft 65, see Figs. 3, 4 and 5. This shaft 65 has secured thereto a disk 66 (Fig. 5) formed with a cam groove 67, in which plays a roller 68 projecting from a pitman 69. The lower end of this pitman is forked so as to straddle the shaft 65, while the upper end thereof 40 is connected to an arm 70 rigid and extending rearwardly from the aforementioned shaft 58. Adjacent to each of the side arms 63 of the accumulator frame is the forward end of an arm 71 which extends rearwardly 45 and is secured to the shaft 58. The forward end of each of these arms 71 is provided with a cam slot 72 in which plays the end of the shaft 62 carrying the accumulator elements or wheels 60. The shape of the 50 cam groove 67 formed in the disk 66 (Fig. 5) is such that immediately upon the beginning of rotation of the shaft 65 the pitman 69 will be elevated and rock the arms 70 and 71 in an anti-clockwise direction.

60 This movement of the arms 71, through

their cam slots 72, will carry the pinions 61 of the accumulator wheels into engagement with the pinions 59, which as stated above are constantly in mesh with the actuators 14. This engagement of the accumulator 70 pinions 61 and the pinions 59, forming a part of the actuators, occurs before the actuators are moved.

When the accumulator elements and the actuators are connected, the elements are 75 moved in an additive direction, shown by the full line arrow (Figs. 3 and 4), when the actuators are under control of the five uppermost keys and when the actuators are under the control of the four lowermost 80 keys of the different banks the accumulator elements are driven in a subtractive direction as indicated by the dotted arrows (Figs. 3 and 4).

From this description the theory of operation of the mechanism will be readily understood. An amount of from one to five units is added by direct addition, while an amount of from six to nine units is added by subtracting the complement from the totalizer wheel. This is accomplished by the provision of the two oppositely moving actuators for the differential elements thereof which may be connected to these elements. Which of the two actuators shall be connected is determined by the value of the keys depressed. Thus the keys in addition to determining the extent of movement of the actuators, as has been the case, also determine the direction of movement thereof. As far as known this is the first example in the art of a machine operating to add by the principle of subtracting the complement. It is also the first example wherein the keys of an adding mechanism determine the direction of movement of the adding wheels as well as the extent of their movement. It is therefore desired to claim these features broadly without limitation to the construction employed.

110 It was before stated that a special type of transfer device was required in a machine of this type. When the machine is adding by direct forward movement of the totalizer elements, the ordinary type of transfer, effective when a wheel passes from its nine to its zero position, is employed. An entirely novel control of the transfer mechanism is also provided, effective when additions take place by complementary subtracting movements of the totalizer wheels. This additional control comprises a device for tripping the transfer elements when a register wheel moves at all in a subtracting direction, but means are provided for resetting the tripped transfer device if the register wheel passes through or leaves its zero position. This transfer mechanism may next be described.

115 As each one of the accumulator elements 120

60 makes a complete rotation in an additive direction, shown by full line arrow (Figs. 3 and 4), a tripping tooth 73 projecting from a disk 74 secured to the accumulating element 60 will engage with a prong 75 of a multi-pronged pawl 76, which is pivoted upon a stud 77 projecting from a transfer lever 78, and rock said pawl 76 in a clockwise direction (Figs. 2, 3 and 4). This pawl 76 is provided with an offset 79 which overlaps a trip pawl 80 pivoted adjacent the pawl 76 upon the stud 77, and thereby rocks said trip pawl with it against the tension of a spring 81 connecting said trip pawl with another pawl 82 also pivotally mounted upon the transfer lever 78. The offset 79 of the multi-pronged pawl 76 is held in engagement with the trip pawl 80 by a spring 83 interposed between the trip pawl and the multi-pronged pawl. This rocking of the trip pawl by the disk 74 releases a carrying pawl 84, which is pivoted upon the transfer lever 78 as at 85 and a spring 86 interposed between lugs on the transfer pawl 84 and the transfer lever 78 causes the transfer pawl to rock in an anti-clockwise direction. This movement of the transfer pawl brings a shoulder 87 formed thereon into engagement with a tooth of a ratchet wheel 88 secured to the accumulator wheel 60 of the next higher denomination. After an accumulator element has been fully operated by its actuator, it is rocked out of engagement with the pinion 59 by the cam disk 66, and the transfer lever 78 is then rocked in a clockwise direction about a rod 89 by a disk 90 having a cam groove 91, in which plays a roller 92 mounted on the lower end of the transfer lever 78. This rocking of the transfer lever 40 will cause the tripped transfer pawl 84 to rotate the accumulating element 60, with which it coöperates, one step in its additive direction. During this transfer operation the pawl 84 will be rocked about its pivot 85 in a clockwise direction by the ratchet 88 with which it coöperates so that at the end of the clockwise movement of the transfer lever 78 the transfer pawl 84 will again be latched by the trip pawl 80. Upon the return of the transfer lever 78 to its normal position by the cam groove 91, the parts carried thereby will again be in the position shown in Figs. 3 and 4. The rod 89 upon which the transfer lever 78 is pivotally mounted is supported by the sidearms 63 of the accumulator frame. As thus far described the mode of operation of the transfer mechanism is already known in the art. The mechanism for tripping the transfer devices when addition takes place by complementary subtraction, may next be described. In every operation the register pinions 61 are engaged with the pinions 59 which form a part of the actuating mechanism. This position of engagement is shown

in Fig. 4 and the pinion 59 is in its normal or zero position. Each pinion 59 is provided with a roller 93 projecting from one of the teeth, this roller being normally in a position to engage a trip pawl 82. The subtracting direction of movement of the pinion is shown by the dotted arrow. This pawl 82 is provided with a prong 95 normally resting on the upper surface of a portion of the transfer trip pawl 80. Thus the first movement in a subtracting direction of pinion 59 will cause its roller 93 to engage the inclined portion 94 of pawl 82 and rock it, thus rocking the transfer trip pawl 80 and releasing the transfer pawl 84 precisely as was described in connection with an operation of direct addition. Thus it will be seen that the transfer mechanism is tripped or rendered effective by the first subtracting movement of any accumulator wheel. An example of such an operation would be one where the totalizer wheels stood at fourteen and eight were added thereto. In such an operation the depression of the "eight" key and an operation of the machine would cause the actuating pinion 59 to be moved two spaces in the subtracting direction. The first of these two steps would cause the roller 93 to engage and operate the pawl 82, thus tripping the transfer pawl 80 and permitting the tooth 87 thereon to engage the ratchet 88 secured to the accumulator wheels. Near the close of the operation of the machine the transfer pawl 84 will be operated, moving the tens wheel one step and thus the wheels will indicate twenty-two, which is the proper result.

However, assume the register wheels have indicated twelve and seven is to be added. Here also the units wheel will be moved in a subtracting direction and the transfer mechanism tripped, but clearly no transfer should take place, as the tens wheel should still indicate one. The resetting of the transfer pawl which has been tripped by the subtracting movement of the units wheel of the example is caused as next described. The backward movement of the register wheel will cause its tooth 73 to engage the prong 75 of the trip pawl 76, rocking it in a direction opposite to its movement in an adding transfer operation. This pawl 76 carries a projection 96 adapted to engage an upstanding portion of the transfer pawl 84. Therefore, when the register wheel moves the third step of its movement in the example, that is, when its reading was changed from zero to nine, the transfer pawl 84 which had been tripped by the first movement of the wheel, would be reset by this third movement and no transfer will then take place.

For one exceptional class of operations a still further explanation is necessary. For example, assume the wheels to read "628" and 273 to be added. In this case the trans-

fer from units to tens is the ordinary adding transfer. The tens wheel moves in a subtracting direction and it, therefore, would trip the transfer for the hundreds wheel, 5 but it also passes through "zero" and this tripped transfer device would, therefore, be reset. However, when the transfer device acting on the tens wheel is operated, near the close of the operation, this would 10 move the tens wheel up to its zero position, thereby again tripping the transfer pawl for the hundreds wheel. Thus the wheels which, after being directly operated would indicate "891," would be moved by the 15 transfer devices so as to indicate "901," the correct result. It will be seen that even in this operation the mechanism shown is entirely adequate to cause the transfer properly to take place.

20 Pawls 150 mounted upon the rod 89 are spring pressed into engagement with the pinions 61 of the accumulator wheels 60 for the purpose of preventing accidental displacement of said wheels.

25 As shown in Fig. 2 of the drawings, an indicating mechanism is provided which mechanism is so constructed as to be moved from one position to another without returning to a normal starting position. This 30 indicating mechanism is operated as follows:

Pivotedly mounted at its forward end to the actuator 14 as at 97 (Figs. 2 and 3) is a beam 98, the extreme rearward end of which is connected by link 99 to an arm 100 secured to one of a series of transverse shafts 101. The arm 100 is connected to a pivotally mounted segmental plate 102 by a link 103. This plate 102 is provided with teeth 104, which mesh with a pinion 105 secured 35 to an indicator drum 106 loosely mounted upon a transverse shaft 107, which is supported by the side frames 5 of the machine. The segmental plate 102 is further provided with alining notches 108, into which enters 40 a pawl 109 fast to a rock shaft 110. Rigid to and projecting forward from this rock shaft 110 is an arm 111 which is connected to the upper end of a pitman 112, the lower end of the latter being slotted so as to straddle the main driving shaft 46 (Fig. 9). Projecting from the lower end of this pitman 112 is a roller 113, which plays in a cam groove 114 formed in a disk 115 secured to the shaft 46. The shape of the cam groove 45 is such that immediately upon the beginning of rotation of the shaft 46, the pitman 112 will be moved downwardly and through arm 111 connected to the upper end of said pitman, rock the shaft 110 and the alining 50 pawls 109 in an anti-clockwise direction thereby freeing the segmental plates 102. The actuators 14 are then adjusted under control of the keys 1, as previously described, by which movement the forward end 55 of the beam 98 will be raised or lowered de-

pending upon the direction of movement of the actuator 14. During the positioning of said actuators a shaft 116, carrying a forked lever 117 for each actuator, will be rocked in a clockwise direction, by which movement the forked portion of each lever will engage with a roller 118 centrally mounted upon the beam 98. If the amount to be indicated is different from that previously indicated, one of the prongs of the forked members 70 of the lever 117 will engage with the roller 118 and move said roller upwardly or downwardly until it passes into the crotch of the forked portion of the lever 117. This movement of the roller will cause the rearward 75 end of the beam 98 to rise or fall and thereby cause the indicator 106 to be adjusted to its new position through the intervening connections from the rear end of the beam 98 to the segmental plate 102.

80 After the indicators 106 have been positioned, the cam disk 115 (Fig. 9) will elevate the pitman 112 so as to rock the shaft 110 (Fig. 2) in a clockwise direction and thereby carry the pawls 109 into the proper 85 alining notches 108 of the segmental plates 102 and lock said indicators in their adjusted position, after which the actuators 14 are restored to their normal position, it being understood that the forked levers 117 are 90 withdrawn from engagement with the rollers 118 of the beams 98 to permit of this restoration of the actuators 14. The shaft 116 carrying the forked levers 117, of which there is one for each actuator, has extending 95 upwardly therefrom an arm 119, which is connected by a link 120 to an arm 121 secured to the lowermost rock shaft 490 (Fig. 2), from which it will be seen that as the actuators 114 are being positioned by the 100 driving segments 16, the indicators are also being positioned by the forked levers 117 engaging with the rollers 118 of the beams 98. 105

The purpose of connecting the beams 98 to the segmental plates 102, through the 110 transverse shafts 101 and link 103, is to enable the connecting up of an additional set of indicators for indicating at the back of the machine and also to position type carriers when it is desired to use the same for 115 recording the amounts indicated and accumulated, it being understood that each of the shafts 101 is connected to one of the actuators in a manner similar to that shown in Fig. 2.

120 The depressed keys are released near the end of the operation of the machine by the following mechanism.

Each one of the links 11 supporting the upper end of a key detent 7 is of a bell 125 crank formation, the free end of which is forked (Fig. 7). Through the forked portion of all of the links 11 extends a rod 140 supported by arms 141 extending forwardly from a rock shaft 142. Near one 130

end this shaft has projecting forwardly therefrom an arm 143, which is fastened to the upper end of a pitman 144, the lower end of the latter being forked so as to straddle the shaft 46 (Fig. 8). This pitman 144 near its lower end is provided with a roller 145, which plays in a cam groove 146 formed in a disk 147 secured to said shaft 46. As this shaft nears the end of rotation 10 the pitman 144 is lowered and, through arm 143, rocks the shaft 142 in an anti-clockwise direction. This rocking of the shaft 142 will cause the rod 140 carried by the arms 141 to engage the lower members of the 15 forked portion of the links 11 and rock said links in a clockwise direction, by which movement the detents 7 will be elevated and the depressed keys 1 released.

To prevent the release of the depressed 20 keys by the release lever 130 during an operation of the machine, the cam groove 146 of disk 147 (Fig. 8) is so shaped that upon the beginning of rotation of the shaft 46 the pitman 144 will be elevated and, 25 through the arm 143 and rock shaft 142, elevate the rod 140 (Fig. 7) to bring it in engagement with the upper members of the forked portions of the links 11 and thereby prevent the rocking of said links to elevate 30 the detents 7. This mechanism will remain in this position until near the end of the operation of the machine when the rod 140 will be lowered to release the keys as above described.

35 The machine is shown as being operated by a crank handle 122 (Fig. 1) but it is to be understood that any other well known form of driving mechanism may be employed. This crank handle 122 has secured 40 thereto a pinion 123 which meshes with a gear 124 suitably mounted upon the framework of the machine. This gear 124 meshes with a large intermediate gear 125, which in turn meshes with gears 126 and 127 secured to the rotary shafts 46 and 65 respectively. This gearing is so proportioned 45 that for every two rotations of the crank handle the shafts 46 and 65 will be given a single rotation.

50 It will be noted from the foregoing description that in so far as the operator of a machine of the described type is concerned, the operation thereof is exactly like that of any of the many well known forms of adding machines or cash registers. No attention is paid by the operator to the direction or extent to which the parts are to be actuated, as said parts are automatically controlled by the novel form of mechanisms provided.

55 As before stated, it is thought that the theory of operation of this mechanism has not been previously suggested in the art. As far as known there is no suggestion in 60 the art of any machine operating partly or

wholly on the principle of complementary subtraction to add amounts. The mechanism which carries out this theory of operation in the present device is also believed to be broadly novel, especially in respect to 70 the movement of the accumulating elements in the shorter of the possible directions, at each operation; in respect to the provision of an actuator variably movable in different directions; and a series of manipulative devices 75 determining both the extent and direction of movement of the actuator. Again, it is believed to be entirely novel to provide a transfer mechanism operative in a constant sense or direction but rendered 80 effective by the movement of the accumulating elements in either direction. In the embodiment shown one set only of transfer elements is employed, but it is to be understood that the invention is not to be limited 85 to this mode of operation, but that other types of transfer mechanism coming within the scope of the claims may be employed.

While the form of mechanism herein shown and described is admirably adapted 90 to fulfil the objects primarily stated, it is to be understood that it is not intended to confine the invention to the one form of embodiment herein shown and described, as it is susceptible of embodiment in various 95 forms, all coming within the scope of the claims which follow.

What is claimed is:—

1. The combination with an accumulator comprising a plurality of movable elements, 100 and means for always moving said elements in the shorter direction in the accumulating of items thereon.

2. The combination with an accumulator comprising a plurality of movable elements, 105 of means for moving said elements in the shorter direction in the accumulating of items thereon, and transfer devices for said elements rendered operative in either direction of movement of the accumulator elements.

3. In a machine of the class described, the combination with a plurality of accumulating elements, of means for always moving said elements in the shorter direction in the 115 entering of items thereon, and manipulative means controlling said moving means.

4. In a machine of the class described, the combination with a plurality of accumulating elements, of means for moving said elements in the shorter direction in the entering of items thereon, manipulative means controlling said moving means, and transfer devices for said elements rendered operative 120 in either direction of movement of the accumulating elements.

5. In a machine of the class described, the combination with an accumulator, of actuators and transfer devices therefor, and means controlling the accumulator, actuators and 130

transfer devices whereby items are accumulated by said accumulator by subtracting from the latter the denominational complements of the item to be accumulated.

5 6. The combination with an accumulator of means coöperating therewith in such a manner that an item is partially accumulated thereon by adding the item to or subtracting the complement thereof from the 10 accumulator depending upon the amount to be accumulated, and transfer devices adapted to complete the accumulation rendered operative by either adding the item or subtracting the complement.

15 7. The combination with accumulating elements of means coöperating therewith in such a manner that an item is partially accumulated thereon by moving the elements in either an adding or subtracting direction 20 depending upon the amount of the item to be accumulated, and transfer devices adapted to complete the accumulation rendered operative by the movement of the elements in either an adding or subtracting direction.

25 8. In a machine of the class described, the combination with an accumulator having a plurality of denominational elements, of actuators for moving said elements either in an additive or subtractive direction, devices 30 for transferring from an accumulator element of lower to an element of higher denomination, and means for rendering said transfer devices operative in either direction of movement of the accumulator elements.

35 9. In a machine of the class described, the combination with an accumulator having a plurality of denominational elements, of actuators for moving said elements either in an additive or subtractive direction, and devices for transferring from an accumulator element of lower to an element of higher denomination, the said devices being under the control of the actuators when the 40 elements are moved in a subtractive direction and under the control of said elements when they are moved in an additive direction.

45 10. In a machine of the class described, the combination with an accumulator having a plurality of denominational elements, of actuators for moving said elements either in an additive or subtractive direction, devices for transferring from an accumulator element of lower to an element of higher denomination, means for rendering said transfer devices operative in either direction of movement of the accumulator elements, and means for rendering said devices inoperative 50 if the elements pass "0" in a subtractive direction.

55 11. In a machine of the class described, the combination with an accumulator having a plurality of denominational elements, of actuators for moving said elements either in

an additive or subtractive direction, devices for transferring from an accumulator element of lower to an element of higher denomination, means controlled by the actuators for tripping the transfer devices every 70 time the elements are moved in a subtractive direction, and means controlled by the elements for recocking said transfer devices if the elements pass "0" in a subtractive direction. 75

12. In a machine of the class described, the combination with an accumulator having a plurality of denominational elements, of actuators for moving said elements either in an additive or subtractive direction, devices 80 for transferring from an accumulator element of lower to an element of higher denomination, and independent means for tripping the transfer devices when the accumulator elements are moved in either an additive or subtractive direction, with provisions 85 for rocking the transfer devices by the additive tripping means after the subtractive means have tripped said transfer devices providing the accumulator elements pass "0" 90 in a subtractive direction.

13. In a machine of the class described, the combination with an accumulator element, of an actuator therefor movable in different directions, and means for determining the direction of movement of said actuator. 95

14. In a machine of the class described, the combination with an accumulator element, of an actuator therefor variably movable in different directions, and means for determining the extent and the direction of movement of said actuator. 100

15. In a machine of the class described, the combination with an accumulator element, of an actuator therefor variably movable in different directions, and a series of keys for determining the extent and the direction of movement of said actuator. 105

16. In a machine of the class described, the combination with an accumulator element, of an actuator therefor variably movable in different directions, driving mechanism for said actuator normally disconnected therefrom, and a series of keys controlling the connection of the actuator and the driving mechanism and also determining the extent and the direction of movement imparted to said actuator by the driving mechanism. 110

17. In a machine of the class described, the combination with an accumulator element, of an actuator therefor variably movable in different directions, driving mechanism for said actuator, normally inoperative devices 125 carried by the actuator for connecting the driving mechanism and the actuator, and a series of keys controlling the connection of the actuator and the driving mechanism and also determining the direction and extent 130

of movement imparted to said actuator by the driving mechanism.

18. In a machine of the class described, the combination with an accumulator element, 5 of an actuator therefor variably movable in different directions, driving mechanism for said actuator, devices carried by the actuator for connecting the driving mechanism and the actuator, operating means for the 10 driving mechanism, a series of keys for determining the extent and direction of movement of the actuator, and means actuated by the keys and the operating means for controlling the devices connecting the actuator 15 and the driving mechanism.

19. In a machine of the class described, the combination with an accumulator, a series 20 of keys, and means controlled thereby for actuating said accumulator in the shortest direction in the accumulation of items thereon.

20. In a machine of the class described, the combination with an accumulator, an actuator therefor operable in the shortest direction 25 to actuate said accumulator in the accumulation of items thereon, duplicate driving means for driving said actuator in opposite directions, manipulating means and devices controlled thereby for rendering one 30 of said driving means effective.

21. In a machine of the class described, the combination with an accumulator, an actuator therefor operable in the shortest direction to actuate said accumulator in the 35 accumulation of items thereon, duplicate driving means for driving said actuator in opposite directions, manipulative means and devices controlled thereby for rendering one of said driving means effective to drive the 40 actuators in the direction appropriate to the value of the key depressed.

22. In a machine of the class described, the combination with an accumulator, of an actuator therefor capable of movement in an 45 additive or subtractive direction in the accumulations and means for controlling the direction of movement of the actuator dependent on the value of the amount to be added.

23. In a machine of the class described, the combination with an accumulator comprising a series of accumulating elements, of a series of actuators therefor each appropriate to a certain numerical order and capable 55 of movement in either an additive or subtractive direction in the accumulation of amounts on said totalizer element, manipulative means and driving means controlled by said latter means for independently driving 60 each of said actuators in the direction requiring shortest movement.

24. An accumulating wheel, means cooperating therewith for actuating said wheel forwardly or reversely in the addition of 65 items thereon according to the value of the

items, and devices for automatically controlling the direction and extent of said actuation.

25. In a calculating machine, the combination with means movable in the shortest direction in calculating operations, and devices for controlling the direction and extent of movement of said means according to the numerical value of the digits of the items of calculation. 75

26. In a machine of the class described, the combination with a totalizer actuator having a normal starting point and capable of differential movement in either direction from said point, of operating means for said 80 actuator, and means for controlling the direction and extent of movement of the actuator.

27. In a machine of the class described, the combination with an accumulator element, 85 of an actuator therefor, means for moving said actuator in opposite directions from a normal position, and latch mechanisms, controlled for connecting the actuator and moving means so that the actuator may be moved 90 in either direction.

28. In a machine of the class described, the combination with an accumulator element, of an actuator therefor, means for moving said actuator in opposite directions from a 95 normal position, a series of keys, and two latch mechanisms, one controlled by certain keys in the series for connecting said actuator and said moving means so that the actuator is moved in one direction, and the 100 other controlled by the remaining keys for connecting said actuator and moving means so that the actuator is moved in the other direction.

29. In a machine of the class described, the combination with an accumulator element, 105 of an actuator therefor, means for moving said actuator in opposite directions, two latch mechanisms for connecting said actuator and said moving means so that the actuator may be moved in either direction, and manipulative means for selecting one or the other of said latch mechanisms to connect the actuator and moving means during an 110 operation of the machine. 115

30. In a machine of the class described, the combination with an accumulator element, of an actuator therefor, means for moving said actuator in opposite directions, two latch mechanisms for connecting said actuator and said moving means so that the actuator may be moved in either direction, and keys for selecting one or the other of said 120 latch mechanisms to connect the actuator and moving means during an operation of 125 the machine, and for controlling the extent of movement of the actuator.

31. In a machine of the class described, the combination with an accounting element, of an actuator therefor, means for moving said 130

actuator in opposite directions, two normally ineffective latch mechanisms, for connecting said actuator and said moving means so that the actuator may be moved in either direction, and a bank of keys for rendering one or the other of said latch mechanisms effective upon operation of the keys and for disabling the effective latch mecha-

nism during the operation of the moving means.

In testimony whereof I affix my signature in the presence of two witnesses.
